LIMIT SWITCH

Allen A. Dicke, Montclair, N. J., assignor to Crown Controls Company, Inc., New Bremen, Ohio, a corporation of Ohio

Application November 16, 1948, Serial No. 60,210

6 Claims. (Cl. 200—138)

1

This invention relates to an improved limit switch and particularly to thermostatically controlled electrical switches and more particularly to a duplex apparatus for automatically opening and closing different circuits alternately.

An object of this invention is to provide a switch of this type providing for rapid or snap-action. Another object is to provide a switch of this type comprising a flexible arm carried by an abutment and having a free end cooperating with a contact, the arm being formed between its ends with convolutions to increase the resiliency thereof without increasing the distance from the abutment to the contact.

While the present invention is applicable to a wide range of uses, for illustrative purposes, but without intent to unduly limit the application or scope of the invention, it is herein shown and described as an automatic heating furnace control for either "hold fire" or "high limit" operation for which it is especially desirable, but obviously is not limited thereto. The present instrument may be so mounted as to be responsive to temperature fluctuations of a furnace jacket bonnet or of a flue pipe or stack and serve to energize damper actuating means or fuel feeding mechanism as necessitated by heating requirements.

The present invention is a further development of an improvement on that disclosed in application for Letters Patent of Wilhelm C. Muth, Serial Number 683,054, filed July 12, 1946, now Patent No. 2,516,525, granted July 25, 1950. Said Muth application contemplates a limit switch of similar construction providing for snap-action contact operation by means of permanent magnets acting upon the contact arms. Due to the limited space available said prior construction utilized magnets which tend to pull the contact arms in the same direction as that toward which they are impelled by the thermo-responsive mechanism. This was found to be unsatisfactory under certain conditions and it is an object of the present invention to overcome said difficulties and to provide a magnetically restrained snap-action limit switch in which a permanent magnet is so related to the contact blade as to temporarily restrain the contact blade against the action of the thermo-responsive actuator.

Another object is to provide such a switch in which the contacts are so arranged that the gap between contacts which are about to be closed is first gradually increased and is thereupon rapidly closed, thus increasing the velocity of closure.

With the above primary and other incidental

2

objects in view as will more fully appear in the specification, the invention intended to be protected by Letters Patent consists of the features of construction, the parts and combinations thereof, and the mode of operation, or their equivalents, as hereinafter described or illustrated in the accompanying drawings.

In the accompanying drawings, wherein is shown the preferred, but obviously not necessarily the only form of embodiment of the invention:

Fig. 1 is a front view of an assembled thermostatically energized electric limit switch illustrating the present invention, the cover having been removed.

Fig. 2 is a vertical, longitudinal cross-sectional view taken on the line 2—2 of Fig. 1.

Fig. 3 is a fragmentary cross-sectional view taken on the line 3—3 of Fig. 1.

Fig. 4 is taken along line 4—4 of Fig. 1.

Fig. 5 is a fragmentary front view of part of the mechanism shown in Fig. 1, but on an enlarged scale showing in dotted lines the position of the switch blade when in normal unactuated position and showing in full line the switch blade when partly actuated and just prior to its movement from one contact to the other.

Fig. 6 is a view similar to Fig. 5 with the parts shown in the positions which they occupy after the switch blade has been actuated, and Fig. 7 is a diagrammatic view of a system of electrical circuits under control of a limit switch of the type shown in Figs. 1 to 6.

Like parts are indicated by similar characters of reference throughout the several views.

In the drawings, 1 indicates a helically wound bimetal thermally responsive element through which extends a rock shaft 2, to the extremity of which one end of the bimetal element 1 is attached at 3.

The opposite end of the thermally responsive spring 1 is attached to a relatively fixed sleeve 4 through which the shaft 2 axially extends. This thermally responsive portion of the apparatus may be enclosed in a tubular heat conductive housing (not shown in drawings) closed at its extreme end and has at its opposite end a lock collar 7 surrounding the sleeve 4 and engageable with a mounting plate 8, which may be attached to a portion of a furnace jacket bonnet wall or a portion of a flue or stack pipe.

Mounted on the forward end of the sleeve 4 is a housing 9 enclosing the contact members, their mounts and the actuating head, and having therein a bearing 2a for the shaft 2, mounted on a bridge 9a within the housing 9. Carried on the

flanged face of the housing 9 are two contact mounting segments. One such mounting segment 11 is normally fixed, but is adjustable within the range of segmental slots 12 through which engage clamp screws 14. The other mounting segment 15 is pivotally mounted concentrically with the housing 9 preferably on the rock shaft bearing 2a for manual oscillatory adjustment thereabout. On each of the mounting segments 11 and 15 a bracket 16 is mounted for oscillatory adjustment about a pivot 17 within the range of an arcuate slot 18 through which a clamp screw 19 extends. Each of the brackets 16 carries a flexible spring contact arm or blade. The spring arm or blade 20 of the stationary mounting segment 11 is alternately engageable with each of a pair of relatively spaced contacts 21 and 22. The corresponding adjustable mounting segment 15 carries a spring contact arm 23 alternately engageable with spaced contacts 24 and 25. The spring arms 20 and 23 are normally biased toward each other by adjustment of the brackets 16, whereby they tend to engage the innermost contacts 21 and 24 of the respective pairs thereof, under the inherent tension of the spring arms 20 and 23. Fixedly attached to the end of the rock shaft or stem 2, for unison motion intermediate the spring arms 20 and 23 is an oscillatory actuating member or cam 26. The cam 26 is rotated to and fro as the bimetal thermally responsive element is actuated in accordance with fluctuations of temperature. The cam 26 may engage one or the other of the spring arms, thereby overcoming the inherent bias of the engaged spring arm and breaking its contact with the inner or normally engaged contact 21 or 24 causing it to engage the other contact of the particular pair thereof.

In order to give to the spring arms actuated by the oscillatory cam a snap-action and definition to their movement, permanent magnets 21' and 24' are mounted on the corresponding mounting sectors adjacent to the contacts 21 and 24, respectively, which accelerates its movement and insures firm contact engagement.

A detachable cover cap 28 engageable with the housing 9, encloses the spring arms, contacts and oscillatory sector. An arm 29 upon the adjustable mounting segment 15 extends beyond the periphery of the housing 9 and cover cap 28, to enable the segment 15 and with it the spring arm 23 and coacting contacts 24 and 25, to be shifted circumferentially, thereby advancing or delaying the engagement of the cam 26 with the arm 23 and movement of the latter away from contact 24 into engagement with contact 25. When under increased temperature, the stress of the bimetal element increases, and the shaft or stem 2 is rocked to move cam 26 out of its engagement with the spring arm 20 the latter disengages the contact 22 and by its inherent tension returns to engagement with the opposite contact 21. By continued rotation the cam 26 engages the opposite spring arm 23 to break its contact with the contact 24 and flex the arm into engagement with the companion contact 25. The interval between the release of the spring arm 20 and engagement of the spring arm 23 is dependent upon the degree of rotative setting of the adjustable mounting segments 11 and 15. The adjusting arm 29 cooperates with a graduated scale upon a lip or segment 30 projecting from the housing 9 having thereon a range of graduations from "Mild" through "Normal" to "Cold." The arrangement is such that a lower temperature is required to cause the cam 26 to engage the spring

arm 23 when the mounting segment 15 is at one limit of its range of adjustment (Mild) than when it is oscillated to the opposite limit of its range of movement (Cold).

5 A connection panel 31 surmounts the housing 9 having thereon a series of circuit terminals, the conductors from which extend through the wall of the housing 9 to the various contacts.

10 Because of excessive range of temperature tending to actuate the cam 26 to an extreme position no positive stop is provided, but after having initially actuated the engaged spring arm, the cam 26 is capable of further idle operation in which the cam periphery merely wipes upon the spring arm under continuing influence of the thermostatic spring 1 without further moving the engaged spring arm and therefore without straining or breakage of parts, and without causing the springs, either contact or thermostatic, to take a definite set.

15 In operation, the switching unit functions as a "hold-fire" or "high-limit" control, depending upon the condition of the fire as is reflected by the bonnet or stack temperatures. If the fire is within normal limits, the cam 26 does not contact either spring arm 20 or 23. These arms therefore remain in their normal or biased positions, in engagement with the contacts 21 and 24 respectively. In this position, the switching unit 20 performs merely a coupling function, serving as a terminal board through which the furnace control 32 is operatively connected with the room thermostat 13. So long as the switching unit 25 remains in its normal position, operation of the furnace control unit 32 is under the sole control of the room thermostat, and responds to a call 30 for heat by the room thermostat increases combustion in the furnace, or by reducing combustion in the furnace when the room thermostat is satisfied.

35 40 Power for the furnace control 32 is supplied by the secondary of a transformer 34 through the wires 35 and 36. The room thermostat and the limit switch comprising the subject matter of the present invention are connected to the furnace control by means of the terminals 37, 38 and 39. Terminal 38 is the "off" or stop terminal while the terminal 39 controls the "on" or start operation of the control 32. The two circuits are completed through the common terminal.

45 50 As shown in Fig. 7 the system is in its "off" or stop position. Should the room thermostat 33 call for heat, the arm will move from the "off" or stop contact 40 to the "on" or start contact 41. This movement of the room thermostat moves the furnace control unit 32 to its "on" or start position, it being energized by the following circuit; from the common terminal 37 conductor 42 leads to terminal 43 on the panel 31 of the switching unit. From there, through 55 the internal wiring of the limit switch, the current is carried through conductor 44 to the spring arm 23 and thence through contact 24 and conductor 45 to the terminal 46 on the panel 31. From terminal 46 conductor 47 leads to the room thermostat 33. The circuit is completed from the thermostat through contact 41, conductor 48 to the terminal 49 on the panel 31, and thence through conductor 50 to terminal 39 of the furnace control 32.

60 70 The furnace control remains in its "on" or start position until the room thermostat 33 is satisfied, at which time, the thermostat moves from contact 41 to contact 49 thereby moving the furnace control to its "off" or stop position.

75 76 The circuit for the "off" movement of the fur-

nace control is the same as for the "on" movement from the common terminal 37 of the furnace control to the thermostat 33. From the thermostat however, the circuit is completed through contact 40 and conductor 51 to terminal 52 on the panel 31. From terminal 52, the internal wiring of the switching unit carries the current through conductor 53 to the spring arm 20, thence through contact 21, conductor 54, conductor 55 to terminal 56 on the panel 31. Conductor 57 interconnects terminal 56 with the "off" or stop terminal 38 on the furnace control thereby completing the circuit to move the furnace control to its "off" position.

Should an abnormal fire condition arise at any time, such condition is rectified by automatic operation of the limit switch of the present invention. For example, if during the "on" period of operation of the furnace control, as called for by the room thermostat 33 the flue or bonnet temperature should become dangerously high, the present switching unit responds to such abnormal condition by energizing the "off" or stop circuit of the furnace control. An increase in flue or bonnet temperature causes clockwise rotation of the cam 26 thereby moving the spring arm 23 away from contact 24 and into engagement with contact 25. Such movement of the arm 23 opens the circuit to the room thermostat thereby eliminating the overall control by the room thermostat, and substitutes a circuit to the "off" or stop terminal 38 of the furnace control. The new circuit is the same as before described from the common terminal 37 of the furnace control to the spring arm 23. From the arm 23 however, the circuit is completed through contact 25, conductor 55, terminal 56 on the panel 31 and conductor 57 to the "off" or stop terminal 38 of the furnace control. The furnace is therefore shut off because of the increase in the flue or bonnet temperature above a predetermined safe maximum.

Another abnormal condition which is cared for and controlled by the present switching unit, is a decrease in flue or bonnet temperature when the room thermostat does not call for heat during extended periods. These periods usually occur in the early fall and late spring, when because of the ambient temperature, the thermostat remains satisfied for long periods of time. During these periods it is quite possible for the fire to become quite low, or extinguished because of the lack of periodic firing operations. The low fire is reflected by a decrease in the stack or bonnet temperature, and when such temperature falls below a predetermined minimum, the cam 26 of the present switching unit by movement in a counter-clockwise direction, moves the spring arm 20 from contact 21 into engagement with contact 22. Such movement of the arm 20 sets up a new circuit to energize the furnace control so as to move it to its "on" or start position. Such "on" operation of the furnace control is entirely independent of any demand by the room thermostat 33.

Referring again to Fig. 7 in which the system is shown in its "off" or stop position with the room thermostat fully satisfied as shown by its engagement with contact 40, upon movement of the arm 20 into engagement with contact 22, the "on" circuit is completed as follows. From the common terminal 37 of the furnace control the circuit to the thermostat 33 is the same as heretofore explained. The circuit to arm 20 is through contact 40, conductor 51, terminal 52 on the panel 31 and conductor 53. The arm 20

being in engagement with contact 22, conductor 58, terminal 49 on the panel 31, and conductor 50. Thus the furnace control 32 is energized so as to move to the "on" or start position independently of the room thermostat 33.

Should the room thermostat 33 call for heat during the "on" operation of the furnace control under control of the arm 20, the thermostat moves from contact 40 to contact 41, thereby establishing the normal "on" circuit which is completely independent of the "on" circuit controlled by the arm 20. Upon moving of the thermostat from the contact 40 into engagement with the contact 41, the special control circuit through the arm 20 is broken thereby relieving the switch 20-22 of all control functions, even though the arm 20 remains engaged with the "on" contact 22.

The contact surface of the cam or actuator 26 is concentric with its axis of rotation whereby it makes only point engagement with one or the other of the straight flat circuit closing arms. The construction is such that after having initially engaged and moved the circuit closing arm, the actuator may continue to rotate to greater or less degree, without varying the adjustment of the circuit closer arm.

Referring to Fig. 3, it will be noted that contact 24 is in the form of a rivet passing through a ring shaped permanent magnet 24' and through a hole in the L-shaped bracket 24'', which bracket is mounted on the segment 15 by means of a rivet 24a and preferably also passing through a terminal clip 24b to which is connected the conductor 45. The contact blade 23 has riveted to it a washer 24c by means of a contact rivet 24d. The washer is made of soft iron or steel and acts as an armature in relation to the permanent magnet 24'.

Contact 25 is preferably in the form of a rivet carried on a bracket 25'' which may be identical with the bracket 24'' and is held in place by a rivet 25a to which is connected, underneath segment 15, the conductor 55. It will be noted that the brackets 24'' and 25'' are reversed in position. This is desirable so that the housing 9 may be made smaller in diameter as it is essential that the rivet 25a be located within the housing 9.

The snap-action operation of the high-limit control switch is more clearly shown in Figs. 5 and 6. Referring to Fig. 5, the dotted lines indicate the position and form of contact arm 23 when not acted upon by cam 26. In full lines is shown the position and form of arm 23 when acted upon by cam 26 but prior to the movement of arm 23 to break contact 24. It will be noted that the attractive force of magnet 24' on its armature 24c is sufficient to cause considerable distortion or flexing of arm 23, considerable energy being stored therein. As soon as the distortion of arm 23 becomes great enough to overcome the power of magnet 24' contact 24 is opened and the blade 23 moves rapidly to close contact 25. This is done by utilizing the energy stored in spring 23. By forming spring 23 with S shaped convolutions such as shown, the flexibility is substantially increased without increasing the distance from the point of support of spring 23 on bracket 16 to the contacts. Therefore, it is possible to get the desired action in an instrument of much smaller dimensions than if a straight arm 23 were used as in the Muth application referred to. It will also be noted that during the first action of cam 26 on arm 23 the

gap of contact 25 is increased. This is most desirable in that the subsequent closing movement of contact 25 is therefore much more rapid. This action is made possible by locating the contacts 24—25 at different distances from the supported end of arm 23. Since during the initial stressing of arm 23 the contact 24 acts as a point of oscillation, the elements of contact 25 are separated, thus offsetting any danger of having both contacts closed during that time.

The operation of the low limit switch comprising arm 20 and contact 21—22 is the same as that just described with reference to the high limit switch except that automatic motion occurs as a result of contour clockwise movement of cam 26.

It will be noted that the constructions shown and described will serve admirably to accomplish the objects stated above. It is to be understood, however, that the constructions disclosed above are intended merely as illustrative of the invention and not as limiting as various modifications therein may be made without departing from the invention as defined by a proper interpretation of the claims which follow.

I claim:

1. A limit switch for use in temperature control systems comprising, in combination, a thermo-responsive actuator, a mounting member, a supporting bracket on said mounting member, a flexible contact blade carried by said supporting bracket in a position where it may be engaged by said actuator, and at least one contact carried by said mounting member in a position where it is engageable by said contact blade, a magnet mounted adjacent said contact, and magnetic material associated with said contact arm so that the contact arm is attracted toward said contact, the contact arm being formed with convolutions between the point where it may be engaged by the actuator and the point where it is engageable with the contact, whereby the resiliency of the contact blade is increased so that energy may be stored therein by the actuator while the magnet is holding the contact blade in engagement with the contact, until the convoluted contact blade is strained sufficiently to overcome the pull of the magnet whereupon the contacts will be separated quickly by the energy stored in said convoluted contact blade.

2. A limit switch for use in temperature control systems comprising, in combination, a thermo-responsive actuator, a mounting member, a supporting bracket on said mounting member, a flexible contact blade carried by said supporting bracket in a position where it may be engaged by said actuator, and at least one contact carried by said mounting member in a position where it is engageable by said contact blade, a magnet mounted adjacent said contact, magnetic material associated with said contact arm so that the contact arm is attracted toward said contact, and a second contact on the other side of said contact arm and located further from said supporting bracket than said first contact, the contact arm being formed with convolutions between the point where it may be engaged by the actuator and the point where it is engageable with the first contact, whereby the resiliency of the contact blade is increased so that energy may be stored therein by the actuator while the mag-

net is holding the contact blade in engagement with the contact, until the convoluted contact blade is strained sufficiently to overcome the pull of the magnet whereupon the contacts will be separated quickly by the energy stored in said convoluted contact blade.

3. A limit switch for use in temperature control systems comprising, in combination, a thermo-responsive actuator, a mounting member, a supporting bracket on said mounting member, a flexible contact blade carried by said supporting bracket in a position where it may be engaged by said actuator, and at least one contact carried by said mounting member in a position where it is engageable by said contact blade, a magnet mounted adjacent said contact, and magnetic material associated with said contact arm so that the contact arm is attracted toward said contact, the contact arm being formed as an S-shaped convolution between the point where it may be engaged by the actuator and the point where it is engageable with the contact, whereby the resiliency of the contact blade is increased so that energy may be stored therein by the actuator while the magnet is holding the contact blade in engagement with the contact, until the convoluted contact blade is strained sufficiently to overcome the pull of the magnet whereupon the contacts will be separated quickly by the energy stored in said convoluted contact blade.

4. The combination according to claim 1 wherein in the contact blade is formed of a first section extending from the supporting bracket to a point beyond the point where it is engaged by the actuator, it being then bent back upon itself to form a second section extending to the vicinity of the supporting bracket and is then again bent back upon itself to form a third section extending beyond the first bend to and beyond the contact.

5. The combination according to claim 1 wherein in the contact blade is formed of a first section extending from the supporting bracket to a point beyond the point where it is engaged by the actuator, it being then bent back upon itself to form a second section extending to the vicinity of the supporting bracket and is then again bent back upon itself to form a third section extending in a direction generally parallel to the first section and extending beyond the first bend to and beyond the contact.

6. The combination according to claim 2 wherein in the contact blade is formed of a first section extending from the supporting bracket to a point beyond the point where it is engaged by the actuator, it being then bent back upon itself to form a second section extending to the vicinity of the supporting bracket and is then again bent back upon itself to form a third section extending beyond the first bend to and beyond both contacts.
